UNITED STATES PATENT OFFICE.

ZACHARY T. BLACKMAN, OF NEW ORLEANS, LOUISIANA.

KNIFE-SHARPENER.

1,307,953.

Specification of Letters Patent. Patented June 24, 1919.

Application filed July 13, 1918. Serial No. 244,742.

To all whom it may concern:

Be it known that I, ZACHARY T. BLACKMAN, a citizen of the United States, residing at New Orleans, in the county of Orleans and State of Louisiana, have invented new and useful Improvements in Knife-Sharpener, of which the following is a specification.

This invention relates to new and useful improvements in knife sharpeners and the principal object of the invention is to provide a sharpener, the sharpening elements of which may be reversed or replaced by new ones when desired.

Another object of the invention is to form the device of two members hinged together and adapted to clamp the sharpening elements between them, with means for holding said members in clamping position.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is an elevation of the device.

Fig. 2 is an end view.

Fig. 3 is a cross section of line 3—3 of Fig. 1.

Fig. 4 is a view of the device in partly opened position.

As shown in these views the device consists of two members 1 and 2 of substantially rectangular shape and hinged together by the hinge 3. The said members may be made of any suitable material though I prefer to make them of wood. In their meeting faces are formed recesses 4 which receive

metal plates 5 extending the full length of the members or blocks and having their ends bent at right angles and extending toward each other. Recesses 5 are formed in the bent parts at one end of the device. These plates form a chamber in which are located the sharpening elements 6 which may be of any suitable material though I show a pair of flat files having their ends engaging said recesses 5. The members or blocks are held in closed position by means of a bolt 7 passing through both blocks and receiving a winged nut 8 at its end. In this manner the two files are held together but with sufficient space between them to receive the cutting edge of a knife. By drawing the knife back and forth the same will be sharpened.

I form a recess 9 in the upper face of one block and secure therein a stone 10 so that the cutting edge of the knife may be finished off on this stone.

It will be seen that the files may be reversed so as to bring a new part of the cutting face thereof into position for acting on the knife when the old parts of said files have become worn. When necessary the files may be replaced by new ones.

It is thought from the foregoing description that the advantages and novel features of my invention will be readily apparent.

I desire it to be understood that I may make such changes in the construction and in the combination and arrangement of the several parts, provided that such changes fall within the scope of the appended claim.

What I claim is:

A device of the class described comprising a pair of blocks hinged together and having recesses at the upper parts of the meeting faces, blades in said recesses having their ends bent at right angles, said ends at one end of the block having recesses therein, a flat file carried by each blade, the small ends of the files engaging said recesses, and a bolt passing through the blocks for adjustably securing them together.

In testimony whereof I affix my signature.

ZACHARY T. BLACKMAN.

Copies of this patent may be obtained for five cents each, by addressing the "Commissioner of Patents, Washington, D. C."
